CLAIM

The ornamental design for a portion of a display panel with a graphical user interface of an animated fitness interface element, as shown and described.

DESCRIPTION

FIG. 1 is a front view of a first image in a sequence for a portion of a display panel with a graphical user interface of an animated fitness interface element, showing my new design;

FIG. 2 is a front view of a portion of a display panel with the second image thereof;

FIG. 3 is a front view of a portion of a display panel with the third image thereof; and,

FIG. 4 is a front view of a portion of a display panel with the fourth image thereof.

The appearance of the animated fitness interface element transitions sequentially between the images shown in FIGS. 1-4. The process or period in which one image transitions to another forms no part of the claimed design.

The outermost broken lines shown in the drawings illustrate portions of the display panel that form no part of the claimed design. The remaining broken lines illustrate portions of the graphical user interface that form no part of the claimed design.
